UNITED STATES PATENT OFFICE.

CHARLES J. KLEIN, OF MILWAUKEE, WISCONSIN.

ELECTRIC SWITCH.

1,127,779.

Specification of Letters Patent. Patented Feb. 9, 1915.

Application filed January 28, 1914. Serial No. 815,047.

To all whom it may concern:

Be it known that I, CHARLES J. KLEIN, a citizen of the United States, residing at Milwaukee, in the county of Milwaukee and State of Wisconsin, have invented new and useful Improvements in Electric Switches, of which the following is a full, clear, concise, and exact description, reference being had to the accompanying drawing, forming a part of this specification.

This invention relates to electric switches.

One of the objects of the invention is to provide a simple and efficient electric snap switch which is cheap to manufacture and which is readily adapted for use in a variety of forms of switch devices.

Further objects and advantages will appear hereinafter.

In order to disclose my invention more clearly I have illustrated a preferred embodiment thereof in the accompanying drawing. For illustrative purposes I have shown the switch movement as incorporated in a surface switch device. It is to be understood, however, that the invention is susceptible of additional embodiments and that the movement may be employed in devices other than that shown.

In the drawing, Figure 1 is a side elevation of a switch mechanism; Fig. 2 is a longitudinal cross section of the same applied to a surface switch device; Fig. 3 is a top plan view of the same; and, Fig. 4 is an end view thereof.

The switch mechanism shown comprises, in general, a reciprocable operating member 1, a pivoted contact member 2, and an energy storing connection between the two whereby a snap movement is imparted to the latter upon reciprocation of the former.

Referring more specifically to Fig. 1, the operating member comprises a U-shaped plate 3 having push-buttons 4 fixed at right angles to the opposite uprights. The base 5 of the plate 3 is mounted to slide over a stationary frame 5 fixed to a suitable switch base. An open barrel 6 is carried by the plate 3 and loosely incloses a coil spring 7 which latter supports a steel ball 8, or other suitable roller. The free extremity of the barrel 6 is longitudinally slotted at opposite sides in the direction of reciprocation of the operating member.

The stationary frame 5 is provided with an integral arm 9 bent upright at one side of the barrel 6 and terminating in a down-

wardly bent convex cam 10 above the barrel. The contact 2 is pivotally secured to the arm 9 by a pin 11 and is preferably of such length below its axis as to lie slightly above the peak of the cam 10. The free extremity of the contact is adapted to bridge stationary resilient contacts 12 mounted on the switch base. The cam 10 and lower extremity of the contact 2 are disposed to lie within the slot of the barrel so that the latter may freely pass across the same. The cam surface of the arm 9 engages the spring pressed ball 8 and retains the latter within the barrel.

The arrangement of the parts described is such that movement of the operating member 1 carries the ball 8 over the stationary cam 10 to impart pressure to the opposite side of the contact 2, which thereupon changes its position with a snap movement.

The switch mechanism is shown in Fig. 2 as mounted upon a suitable insulating base 13 having a recess within which the operating plate 3 reciprocates and to the bottom of which is fixed the stationary frame 5 by means of screws 14. Two resilient contact members 12 are secured to the base by screws 15 at opposite sides of the switch operating member and at one end of the base. These stationary contacts are provided with contact surfaces 16 at one extremity and binding posts 17 at their other extremities. Openings 18 are provided in the base on opposite sides of the same adjacent the binding posts for the reception of line wires entering the device for connection to the switch terminals.

Assuming the switch to be in the "on" position shown in Fig. 1, pressure on the left push-button works as follows: The operating member 1 is moved to the right, thereby carrying the spring-pressed ball 8 toward the apex of the peaked cam 10. As the ball passes this apex the same tends to ride rapidly down the opposite cam face thereby imparting a hammer blow and snap movement to the contact which is oscillated to "off" position. It will be observed that the spring-pressed ball 8 acts to retain both the switch operating member and the contact member in extreme positions. In the form shown, the ends of the frame 5 are bent so as to engage, and to limit the movement of, the operating member. With the switch in "off" position pressure on the

right push-button operates to reverse the position of the contact in a manner similar to that described.

A metallic cover 19 is provided to rest 5 upon the walls of the switch base and house the switch mechanism. A suitable insulating lining 20 is, of course, provided for the cover.

The mechanism described comprises few 10 parts which are cheap to manufacture and which may be easily assembled. Furthermore, the mechanism is of sturdy and compact construction which is efficient in service and not likely to get out of order. The 15 relation of the parts and their mounting upon the insulating base is such that the line terminals and the movable parts of the switch mechanism are completely and easily accessible by removal of the metallic cover 20 19. Furthermore, by projecting the peak of the cam 10 slightly beyond the flat extremity of the contact 2 the spring-pressed ball moves completely over the peak of the cam before engaging the extremity of the contact 22 and consequently imparts a hammer blow to the latter to actuate the same.

What I claim as new and desire to secure by Letters Patent is:

1. In an electric switch, in combination, an 30 operating member, a spring-pressed device movable therewith and restrained against lateral movement relative thereto, a pivotally mounted contact having portions on opposite sides of its axis to be engaged by said device, and a member having an unyielding convex cam with inclined surfaces on opposite sides of the axis of said contact and engaged by said spring-pressed device.

2. In an electric switch, in combination, a 40 reciprocating operating member having a spring-pressed device movable therewith, a stationary member having a convex cam surface engaged by said device and a pivotally mounted contact having a portion at each 45 side of the peak of said cam to be engaged by said device.

3. In an electric switch, in combination, a reciprocable operating member, a spring-pressed device movable therewith and restrained against lateral movement relative thereto, a stationary member having a convex cam surface engaged by said device, and a pivotally mounted contact having portions at opposite sides of its axis to be engaged by 55 said device after the same has passed the peak of said cam.

4. In an electric switch, in combination, an operating member having a spring-pressed device movable therewith, a stationary member having a convex cam surface engaged by said device, and a contact pivoted to said member and having portions at opposite sides of its axis to be engaged by

said device with a hammer blow after the latter has passed the peak of said cam.

5. In an electric switch, in combination, a reciprocable operating member having a spring-pressed device movable therewith a stationary member having a convex cam surface engaged by said device and a contact pivoted to said member and having portions at opposite sides of its axis to be engaged by said device, the peak of said cam projecting beyond the engaged portions of said contact. 75

6. In an electric switch, in combination, a reciprocable operating member, an open-ended barrel carried thereby, a spring pressed ball carried within said barrel, a stationary member having an unyielding convex cam engaged by said ball, and a pivotally mounted contact having portions at opposite sides of its axis to be engaged by said ball after the same has passed over the peak of said convex cam. 85

7. In an electric switch, in combination, a stationary frame having a convex cam, an operating member reciprocable across said frame and carrying a spring-pressed device engaging said cam, and a contact pivoted to 90 said frame adjacent said cam and having portions on opposite sides of its axis to be engaged by said device.

8. In an electric switch, in combination, a base, a member fixed thereto and having a convex cam surface spaced therefrom, reciprocable operating means movable across said base and having a spring-pressed device engaging said cam surface, and a contact pivotally mounted on said member adjacent 100 said cam and having portions on opposite sides of its axis to be engaged by said device with a hammer blow after the same has passed the peak of said cam.

9. In an electric switch, in combination, 105 an insulating base having a recess, a stationary frame fixed to the bottom wall of said recess and having an integral arm with a convex cam surface, a reciprocable operating member movable across said base and limited 110 in its movement by engagement with the ends of said frame, a spring-pressed device carried by said operating member and engaging said cam surface, a contact pivotally mounted on said frame arm adjacent said 115 cam and having portions on opposite sides of its axis to be engaged by said device after the same has passed the peak of said cam, and a pair of stationary contacts mounted on said base to be engaged by said pivoted contact. 120

In witness whereof, I have hereunto subscribed my name in the presence of two witnesses.

CHARLES J. KLEIN.
